UNITED STATES PATENT OFFICE.

ANNA E. DREW, OF NEW YORK, N. Y.

DESIGN FOR A SHELLER FOR GREEN PEAS, &c.

SPECIFICATION forming part of Design No. 26,283, dated November 17, 1896.

Application filed August 12, 1896. Serial No. 602,581. Term of patent 7 years.

To all whom it may concern:

Be it known that I, ANNA E. DREW, a citizen of the United States, residing in the city, county, and State of New York, have invented and produced a new and original Design for Green-Pea and Bean Shellers, of which the following is a specification, reference being had to the accompanying drawing, showing the parts thereof.

10 In the drawing the figure thereof represents a perspective view illustrative of my improved green-pea and bean sheller.

15 The leading features of my design consist of a sheller having a cutting-blade upon the under side thereof, a flange constituting the sheller proper located at the outer end thereof, a recess between the forward end of the cutting-blade and the main body part of the sheller, and a shoulder formed between said 20 recess and said flange.

25 My sheller is made in the form generally of a human hand holding an open penknife, the lower end or point of the blade thereof constituting the cutting edge of the knife. Printed, pressed, or otherwise placed upon the top surface of the sheller is the design of a hand holding an open penknife, with a pod 30 of a pea containing several peas at the forward end thereof.

35 In manufacturing my sheller according to the design herein described the same is

stamped from sheet-steel, the flange 1 constituting the sheller proper afterward turned so that it lies at right angles to the main part of said sheller, and the forward edge and 35 point of the knife portion 2 being afterward sharpened by hand.

In using my pea and bean sheller the same is grasped in the right hand and the pea or bean pod in the left. The knife portion 2 is 40 then inserted into the pod adjacent to the body of the operator and the sheller forced forwardly, cutting the outer edge of said pod. The shoulder formed between the knife 2 and the flange 1 prevents the insertion of the 45 knife to such a degree that the peas or beans themselves will be injured. At the outer end of the stroke of the sheller the same is turned, with the flange 1 fitting between the two parts of the pod, and the device is then 50 drawn rearwardly, forcing the peas or beans from the pod.

Having now described my invention, what I claim is—

The design for a green-pea and bean sheller, 55 substantially as shown and described.

In testimony whereof I hereto affix my seal in the presence of two witnessss.

ANNA E. DREW. [L. S.]
